SPRINKLER FOR EXTINGUISHING FIRES

Eric P. Hanson, North Providence, R.I., assignor to Grinnell Corporation, Providence, R.I., a corporation of Delaware

Filed Oct. 24, 1960, Ser. No. 62,583

Term of patent 14 years

(Cl. D91—1)

FIG. 1

FIG. 2

FIG. 3

The dominant features of my design reside in the portions shown in full lines.

I claim:

The ornamental design for a sprinkler for extinguishing fires, substantially as shown and described.
